UNITED STATES PATENT OFFICE.

HOWARD O. McMILLAN, OF MINNEAPOLIS, MINNESOTA.

WIRE-CUTTING DEVICE.

Application filed July 20, 1927. Serial No. 207,264.

This invention relates to a cutting device and while the device is capable of many uses it particularly has been designed for cutting wire. In concrete work a great deal 5 of wire is used for tying the forms or other purposes, much of which must be cut to certain lengths. The present device has been designed particularly for cutting such wire.

It is an object of this invention to provide 10 a simple device which can be easily and quickly operated to cut wires to the desired length.

It is another object of the invention to provide a simple wire cutting device adapted 15 to be attached to some suitable support having a base plate for said purpose on which upstands a post. This post is adapted to receive a fixed knife and a movable knife and to have pivoted therein at its upper end a handle 20 lever, the lever and movable knife projecting to the rear of said post and being connected by a link, means preferably being provided to pull the link downwardly toward the base to maintain the knives in open position.

25 It is also an object of the invention to provide a device as above set forth in which the normally fixed knife can be adjusted and held in adjusted position.

These and other objects and advantages 30 of the invention will be apparent from the following description made in connection with the accompanying drawings in which like reference characters refer to similar parts throughout the several views and in 35 which:

Fig. 1 is a view in side elevation of the device;

Fig. 2 is a plan view of the device; and

40 Fig. 3 is a vertical section taken on the line 3—3 of Fig. 1, as indicated by the arrow.

Referring to the drawings, a cutting device is shown comprising a base plate 5. While this plate may be of various shapes, 45 in the embodiment of the invention illustrated, the same is shown as substantially rectangular in shape with rounded corners and as having a plurality of holes 5^a therethrough adjacent said corners, which holes 50 are adapted to receive means for securing the base to some suitable support. Said base also has a projecting lug 5^b at its rear end for a purpose to be later described. The base 5 has a post 6 upstanding therefrom disposed substantially at the transverse center 55 of said base and toward one end thereof, said

post having a narrow slot or aperture 6^a extending longitudinally therethrough immediately above the base 5 and having an open ended slot 6^b extending longitudinally therethrough at its upper end, said upper end thus being forked or bifurcated. Post 6 has a lug 6^c of comparatively small height extending forwardly therefrom, which lug has a slot extending longitudinally therethrough of the same width as and aligned with the aperture 6^a. A normally fixed knife 7 is disposed in the aperture 6^a and the slot in lug 6^c, said knife being of a width substantially to fit in said aperture and slot and being fixedly held in position by engagement therewith of a set screw 8 threaded into one side of the post 6. As shown, in Fig. 3, knife 7 is provided with a beveled or sharpened upper edge. The knife 7 can be raised 60 when the same becomes worn by placing thereunder one or more shims 9. A movable knife 10 also extends through aperture 6^a and is pivoted on a headed and nutted bolt 11 extending through the post 6. As shown in Fig. 3, the knife 10 has its lower edge beveled or sharpened. The knife 10 projects rearwardly from post 6 over the base 5 and is received in the lower bifurcated 65 end of link 12, being pivoted to said link 70 by the pin 13, which pin is held in position by the cotter pins 14 extending therethrough. A lever 15 is disposed in the forked top of post 6 having a forwardly extending handle portion 15^a of considerable length, said lever 75 extending rearwardly of post 6 substantially parallel to the knife 10 and having its rear end received in the upper bifurcated end of link 12. The lever 15 is pivoted to post 6 by the headed and nutted bolt 16 passing 80 therethrough and through post 6 and is pivoted to link 12 by the pin 17, which pin is held in place by the cotter pins 18. The link 12 has an apertured lug 12^a projecting 85 rearwardly from its intermediate portion to 90 which is connected the upper end of a coiled tension spring 19, the lower end of which is connected to apertured lug 5^c projecting upwardly from the lug 5^b.

In operation the wire or other material 105 to be cut will be inserted between the separated forward ends of the knives 7 and 10. The spring 14 normally pulls down on link 12 and the rear end of lever 15, thus elevating the front end of knife 10 and holding 110 the knives in separated position. When the wire is inserted between the knives 7 and 10

the operator will push downwardly on the forward end of the handle 15^a, thus raising link 12 and the rear end of knife 10, causing the front end of said knife to move downwardly, bringing the sharpened edge thereof down to the edge of the fixed knife 7 and cutting off the wire or other material. It will be seen that a very great leverage is obtained by the lever 15 and the movable knife. The material is thus very easily cut. The device in practice is fastened to a bench, plank or other suitable support and can be very quickly operated. The wires for use with the concrete can be cut with much less effort and much more speed than with the hand pliers commonly heretofore used.

From the foregoing description it is seen that applicant has provided a very simple and efficient device for cutting wire or other small material. The device comprises few parts and the same can be made and sold at comparatively small expense. The device has been amply demonstrated in actual practice and has been found to be very successful.

It will, of course, be understood that various changes may be made in the form, details, arrangement and proportions of the parts without departing from the scope of the invention which, generally stated, consists in the novel parts and combinations of parts disclosed and defined in the appended claims.

What is claimed is:

1. A cutting device comprising a base, an integral post upstanding from the forward portion thereof having an aperture extending longitudinally therethrough immediately above said base and having a slot extending longitudinally through its upper end and

open at the top thereof, a fixed knife in 40 said aperture resting on said base, means in said post for holding said knife in fixed position, a movable knife extending through said aperture and pivoted to said post above said fixed knife adapted to co-operate therewith and extending to the rear of said post, a lever disposed in said slot in the upper end of said post and pivoted thereto having a handle portion of comparatively great length extending forwardly from said post, 50 said lever extending rearwardly from said post, a link having bifurcated ends in which the rear ends of said lever and movable knife are respectively received and pivoted, and means for normally holding the rear end 55 of said lever downwardly and maintaining said knives separated.

2. A cutting device comprising a base, a post upstanding from said base having a lug at its forward end, said post and lug being provided with a slot which extends through said post longitudinally thereof, a fixed knife resting in the bottom of said slot in said post and base, having its rear end substantially at the rear end of said post, a movable knife extending through the slot in said post and pivoted therein, said movable knife extending rearwardly over said base, a lever pivoted in the upper end of said post, extending substantially parallel to said movable knife and extending to the rear of said post and having a handle portion extending forwardly of said post and a link connecting the rear ends of said lever and movable knife.

In testimony whereof I affix my signature.

HOWARD O. McMILLAN.
